Primary Examiner — Cynthia Ramirez*Assistant Examiner* — Laura H Yu(74) *Attorney, Agent, or Firm* — Kilpatrick Townsend & Stockton LLP(57) **CLAIM**

The ornamental design for a shoe, as shown and described.

DESCRIPTION

FIG. 1 is a rear lateral perspective view of a shoe showing our new design.

FIG. 2 is a rear medial perspective view of the shoe of FIG. 1.

FIG. 3 is a lateral side view of the shoe of FIG. 1.

FIG. 4 is a medial side view of the shoe of FIG. 1; and, FIG. 5 is a rear view of the shoe of FIG. 1.

The broken lines show unclaimed subject matter only and form no part of the claimed design.
